(57) **CLAIM**

We claim the ornamental design for a single battery pack inverter, as shown and described.

DESCRIPTION

FIG. 1 is a front perspective view of a single battery pack inverter according to one construction.

FIG. 2 is a front view of the single battery pack inverter shown in FIG. 1.

FIG. 3 is a rear view the single battery pack inverter shown in FIG. 1.

FIG. 4 is a first side view the single battery pack inverter shown in FIG. 1.

FIG. 5 is a second side view the single battery pack inverter shown in FIG. 1.

FIG. 6 is a top view the single battery pack inverter shown in FIG. 1.

FIG. 7 is a bottom view the single battery pack inverter shown in FIG. 1.

FIG. 8 is a front perspective view of a single battery pack inverter according to another construction.

FIG. 9 is a front view of the single battery pack inverter as shown in FIG. 8.

FIG. 10 is a rear view of the single battery pack inverter as shown in FIG. 8.

FIG. 11 is a first side view of the single battery pack inverter as shown in FIG. 8.

FIG. 12 is a second side view of the single battery pack inverter as shown in FIG. 8.

FIG. 13 is a top view of the single battery pack inverter as shown in FIG. 8; and,

FIG. 14 is a bottom view of the single battery pack inverter as shown in FIG. 8.

The broken lines shown represent the portions of the single battery pack inverter that form no part of the claimed design.
